(57) **CLAIM**

We claim the ornamental design for a refrigerator, as shown and described.

DESCRIPTION

FIG. 1 is a front perspective view of a first embodiment of a refrigerator showing our newdesign;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion 8 shown in FIG. 1;

FIG. 9 is an enlarged view of the encircled portion 9 shown in FIG. 1;

FIG. 10 is an enlarged view of the encircled portion 10 shown in FIG. 5;

FIG. 11 is an enlarged view of the encircled portion 11 shown in FIG. 6;

FIG. 12 is a front perspective view of a second embodiment of a refrigerator showing our new design;

FIG. 13 is a front view thereof;

FIG. 14 is a rear view thereof;

FIG. 15 is a left-side view thereof;

FIG. 16 is a right-side view thereof;

FIG. 17 is a top view thereof;

FIG. 18 is a bottom view thereof;

FIG. 19 is an enlarged view of the encircled portion 19 shown in FIG. 12;

(Continued)

FIG. 20 is an enlarged view of the encircled portion 20 shown in FIG. 12;

FIG. 21 is an enlarged view of the encircled portion 21 shown in FIG. 16; and,

FIG. 22 is an enlarged view of the encircled portion 22 shown in FIG. 17.

The evenly-dashed broken lines in the figures depict portions of the refrigerator which form no part of the claimed design.

The dot-dot-dash broken lines encircling portions of the claimed design that are illustrated in enlargements form no part of the claimed design.

The gray tones shown in the figures indicate that the gray portions are the same contrasting color, and do not represent any particular color.

1 Claim, 18 Drawing Sheets
